UNITED STATES PATENT OFFICE.

FRANZ WOLFF, OF SAN FRANCISCO, CALIFORNIA, ASSIGNOR OF ONE-HALF TO
GEORGE F. BOTSCHEIDER, OF SAN FRANCISCO, CALIFORNIA.

ELEVATOR SWITCH LOCK.

Application filed June 14, 1922. Serial No. 568,338.

To all whom it may concern:

Be it known that I, FRANZ WOLFF, a citizen of the United States, residing in the city and county of San Francisco and State of California, have invented a new and useful Improvement in an Elevator Switch Lock, of which the following is a specification.

My invention relates to improvements in 10 a switch lock for elevators and the like wherein a latch operates to normally lock an elevator door and maintain an electric control circuit in closed condition when the door is closed and to automatically break 15 the control circuit when the door is opened.

The primary object of my invention is to provide an improved switch lock for elevator doors and the like.

Another object is to provide an improved 20 device in which electric circuit closing elements are arranged to be actuated by gravity to maintain a control circuit closed while an elevator door is closed and to break the circuit while the door is open, to prevent 25 operation of the elevator while said door is open.

Another object is to provide an improved construction arranged to insure the breaking 30 of the control circuit when the door is opened and to effectively prevent the closing of the circuit until the door is locked in a closed position, thereby insuring against accident due to premature starting of the elevator.

35 A further object is to provide an improved construction of simple and efficient construction which may be readily installed for operation in conjunction with the ordinary elevator door lock.

40 Other important objects of my invention are to provide improved insulating means, to render the contacting and locking elements separately accessible, and to reduce wear and damage to the contact elements.

45 I accomplish these and other objects by means of the device disclosed in the drawings forming a part of the present specification, wherein like characters of reference are used to designate similar parts throughout said specification and drawings, and in which:

Fig. 1 is a broken front elevation of a portion of an elevator door and sash disclosing the application of my improved lock 55 thereto.

Fig. 2 is a front elevation of my improved switch lock with the outer cover portions removed, the latch being shown in the locking position.

Fig. 3 is a similar view disclosing the 60 latch moved to unlock the door.

Figs. 4 and 5 are sectional views taken upon the lines 4—4 and 5—5 respectively, of Fig. 3 in the directions indicated.

Referring to the drawings the numeral 1 65 is used to designate in general an elevator door operating within a casement 2, said door being provided with a suitable latch 3 of any standard construction such as is commonly installed upon the door of an ele- 70 vator.

Upon the upper portion of the door I provide a latch 4 pivotally mounted upon a suitable mounting 6, the rearward end of said latch being connected with the latch 3 75 by a rod 7 or other rigid connection. The forward portion of the latch 4 is arranged to enter an opening in the proximate side of a switch housing 8 secured upon the casement 2 adjacent the latch 4 when the door 80 1 is closed, said forward portion being notched to form a shoulder 9 adapted to enter into locking engagement with an inwardly disposed extension 10 formed upon the housing adjacent the opening. The 85 latch 4 is normally maintained in locking position as shown in Fig. 2 of the drawings by the weight of the rearward portion of the latch and the connecting rod 7, thereby fastening the door in closed position with 90 additional security and securing against the inadvertent or unauthorized opening of the door.

A stirrup 11 is slidably mounted within the housing 8 upon guides 12 formed upon opposite sides of the housing, said guides being preferably cast as an integral part of the housing. A circuit closing contact 13 is mounted upon the upper end of a post 14 secured in insulated relation upon the top of the stirrup, said contact being secured upon a sleeve 16 having a limited sliding movement upon the post 14 against the pressure of a spring 17 for a purpose hereinafter more fully explained. 100

The stirrup 11 is normally held by its own weight in the lower portion of the housing 8. When the forward portion of the latch 4 enters the housing the point of the latch enters the stirrup, a cam surface 110

18 formed upon the upper side of said point engaging an upper transverse portion 19 of the stirrup and elevating the same to move the circuit closing contact 13 into engagement with a pair of control contacts 21 secured within the upper portion of the housing 8.

The control contacts 21 are insulated from the housing in a manner hereinafter 10 more fully described, and are connected within the elevator control circuit by suitable connecting wires 22 entering the housing through a conduit 23 connected thereto.

The construction of the housing 8 is of 15 particular importance in my invention in that it may be easily and cheaply manufactured and assembled and because it affords a compact and efficient means for insulating the electric contacts, and for the 20 further reason that it provides ready access to the contacts and operating parts for inspection and repair. The housing consists of a substantially rectangular frame 26 having the side opening and inwardly projecting 25 extension above described in connection with the latch 4. Cover portions 27 are secured upon the lower portion of each side of the housing by suitable screws, said portions 27 having the guides 12 above mentioned cast integrally therewith to receive the stirrup 11. Strips 28 of insulating material are inset into the upper portions of the sides of the frame 26 as shown in Figs. 2 and 3, and a strip 29 of insulating material 30 secured upon the inner side of the top of the frame 26, the control contacts 21 being secured upon the strip 29. The upper portions of the sides of the housing are closed by cover portions 31 made of suitable insulating material, the lower edge of each portion 31 matching with the adjacent edge of the adjacent cover portion 27, forming an insulated chamber within the upper portion of the housing. In this manner the 40 contacts are fully enclosed within dielectric material in such manner as to prevent shorting of the circuit should one of the contacts become loosened, and likewise insuring against damage due to arcing. The fact 45 that the upper cover portions 31 of the housing are removable independently from the lower portions 27 is of importance because of the ease with which access may be had to the contacts without disturbing the stirrup and its related elements. In similar 50 manner the lower cover portion may be removed separately to obtain access to the stirrup without disturbing the insulation of the contacts.

55 The device operates in the following manner. When the point of the latch 4 enters the stirrup and is moved, either by the operator or by the weight of the rod 7, into the locking position, the stirrup, riding upon the cam surface 18, is elevated and

the circuit closing contact 13 moved into engagement with the control contacts 21 thereby closing the control circuit which is otherwise broken between said contacts 21. The sliding movement of the sleeve 16 70 against the pressure of the spring 17 insures proper engagement of the contacts and also serves to cushion the impact between the contacts which would otherwise result in excessive wear and damage. The height of 75 the cam surface 18 is so designed that contact will not be made until after the shoulder 9 has been moved into locking engagement with the extension 10, in this manner effectually preventing the starting of the elevator before the door is closed and locked. So long as the door remains locked in the closed position the contacts will be held in circuit closing engagement by the weight 80 of the rod 7 and the elevator may be operating in the usual manner.

When the latch is moved to release the door for opening, the weight of the stirrup will normally operate to break the electric control circuit by lowering the contact 13 90 out of engagement with the contacts 21. However, as contacts of the character described are subject to what is commonly termed "freezing," and often requires a considerable force to effect a separation, I have 95 provided a lower cam surface 32 upon the forward portion of the latch 4 which is arranged to engage a transverse portion 33 of the stirrup when the latch is moved from the locking position. The cam portion 32 is arranged to engage the stirrup before the shoulder 9 disengages the extension 10 as shown in dotted lines in Fig. 2 of the drawings, in this manner insuring that the control circuit be broken prior to the opening of 100 the door. As the circuit will now of necessity remain broken until the latch has again been moved to lock the door in closed position, it will at once be seen that an accident due to premature starting of the elevator 105 will be effectually prevented. The portion 33 likewise prevents the stirrup from being thrown upward by the initial impact of the latch 4 against the upper portion 19 thus preventing a premature contact.

While I have illustrated my improved switch lock in connection with a door of the sliding type, it is to be understood that by a proper arrangement and disposition of the housing and latch 4 the device may be applied to operate in an identical manner in connection with doors of the swinging, folding, or other types commonly installed in elevator construction.

Having thus described my invention what I claim as new and desire to secure by Letters Patent is:

1. In a switch lock for elevators and the like, a housing comprising a frame; insulation secured upon the inner side of the top 130

- and the upper portion of the sides of the frame; front and back covers secured upon the frame, said covers each consisting of a lower portion and an upper portion, formed 5 from a plate of dielectric material, separately removable from the frame as and for the purposes described.
2. In a switch lock for elevators and the like, a housing comprising a frame; insulation secured upon the inner side of the top and the upper portion of the sides of the frame; covers removably mounted upon the front and back of the frame, said cover each consisting of a lower portion having guides 10 formed integrally therewith, and upper portions formed from dielectric material, said upper and lower portions being separately removable; fixed contacts mounted within the insulated upper portion of the frame; 15 and a movable contact slidably mounted upon the guides within the lower portion of the frame, as and for the purposes described.
3. In a switch lock for elevators and the like, a housing comprising a frame; insulation secured upon the inner side of the top and upper portion of the frame; covers removably secured upon the front and back of the frame, said covers each consisting of a lower portion having guides formed 20 integrally therewith upon the inner sides thereof, and an upper portion formed from dielectric material, said upper and lower portions being separately removable; fixed 25 contacts secured within the upper insulated portion of the frame; a stirrup slidably mounted upon the guides within the lower portion of the frame; a movable contact carried by said stirrup, and arranged to engage the fixed contacts, said movable contact being normally held in circuit breaking position by the weight of the stirrup; and a latch pivotally mounted upon the door and arranged 30 to enter the housing to secure the door in closed position, said latch having upper and lower cam surfaces arranged to engage the stirrup to move the stirrup upwardly when the door is closed whereby the movable contact is moved to close a circuit between the fixed contacts, and to move the stirrup downwardly to break said circuit when the door is opened.
4. A switch lock for elevators and the like 35 comprising a housing consisting of a frame mounted adjacent an elevator door; insulation secured upon the inner side of the top and upper portion of the frame; covers removably secured upon the front and back of the frame, said covers each consisting of a lower portion having guides formed integral therewith upon the inner sides thereof, and an upper portion formed from dielectric material said upper and lower portions being 40 separately removable; fixed electric contacts secured within the upper insulated portion of the frame; a stirrup slidably mounted upon the guides within the lower portion of the frame; a movable contact carried by said stirrup, and arranged to engage the fixed contacts, said movable contact being normally held in circuit breaking position by the weight of the stirrup; and a latch pivotally mounted upon the door and arranged 45 to enter the housing to secure the door in closed position, said latch having upper and lower cam surfaces arranged to engage the stirrup to move the stirrup upwardly when the door is closed whereby the movable contact is moved to close a circuit between the fixed contacts, and to move the stirrup downwardly to break said circuit when the door is opened.

In witness whereof I hereunto set my 50 signature.

FRANZ WOLFF.
